THREAD PICKER FOR VACUUM-CLEANER NOZZLES

Ward Leathers, Haworth, N. J., assignor to Quadrex Corporation, New York, N. Y., a corporation of Delaware

Application October 21, 1936, Serial No. 106,763

4 Claims. (Cl. 15—157)

The object of my invention is to produce a means of picking up threads, ravelings, and other tightly embedded bits of litter in rugs and carpets.

5 Vacuum cleaners equipped with motor-driven rotary-brushes have the advantage of picking up such superficial dirt in a more satisfactory manner than plain nozzle cleaners. Plain nozzle cleaners have some advantages in deeper cleaning and less wear and tear on rugs and carpets. Besides, that class of vacuum cleaner wherein the motor-suction-unit is made integral with the handle is lighter and more mobile, and for 10 mechanical reasons the plain nozzle construction 15 is more adaptable. My thread picker is particularly suited to this latter type of machine.

With plain nozzle cleaners, where the nozzle edges or strokers are given sufficient "tooth" to disengage these annoyingly tight bits of litter, they are harder to push and subject to the 20 criticism of carpet injury. Teeth in such strokers sufficiently sharp to disengage all such tight clinging litter would be injurious to rugs and carpets.

25 My invention provides a thread picker which permits smooth strokers edges on the sides of the nozzle so that no injury can be done to carpets and it makes it possible for teeth sufficiently sharp to disengage any litter to come into use when needed at the will of the operator in a manner almost unconscious to the operator and automatic to the machine.

With the type of vacuum cleaner especially referred to, changing the angle at which the handle of the machine is held changes the nozzle angle with the floor in the same degree. When the rigid type machine is used in the free and normal manner my thread picker presents a smooth surface to the carpet. When clinging threads or litter are not disengaged by the 35 free passage of the machine over them the operator unconsciously raises the handle and applies pressure to the nozzle. The functioning of my thread picker depends upon this natural 40 action on the part of the operator. It consists primarily of teeth provided with a spring guard, the guard yielding under pressure.

To make clear my invention I have prepared the following specification to which I have appended a drawing, of which:

45 Figure 1 is a vertical cross section of a nozzle taken at the side of the tubular center portion normally joined to or integral with the fan housing of the motor suction element of a vacuum cleaner.

Figure 2 is a side elevation of a rigid type cleaner showing its operating positions.

Figures 3 and 4 diagrammatically illustrate retractable nozzle wheels.

Figure 5 illustrates a thread picker tooth strip.

Figure 6 illustrates the spring guard in flat or blank form.

A metal nozzle or nozzle frame 1, Figure 1, is so designed that to the inner side of the forward edge a hardened steel piece 2 may be joined as 10 by rivets. This hardened piece or strip is provided with teeth, as shown in Figure 5. To the forward face of the same front portion of the nozzle is joined by screws or other suitable means a spring guard 3. This guard is provided with slots through which the teeth of strip 2 project when the guard is depressed. (It should be understood that Figure 1 illustrates this mechanism in schematic form.) A floor wheel 7 rests on the floor 8. The floor wheel 20 may be of the retractable type so that when the nozzle is pressed downward by the operator for greater agitation or for cleaning low pile carpet the floor line moves upward to a position shown in dotted lines 9. Any type of vacuum cleaner where downward pressure may be applied to the nozzle by the operator could be equipped with this thread picker in practical form. However, greater advantages and practicability of use are available when my thread 25 picker is applied to a rigid handle type machine (as illustrated in Figure 2). When the handle of the machine is raised to a greater angle with the floor because the operator wishes to push the nozzle closer into the carpet in an instinctive action the floor line assumes a position 10 and 30 with the wheel retracted moves to a position shown in dotted line 11. It will be noted that particularly in this last position the pressure of the carpet pile presses the spring guard 3 to the position shown in dotted lines exposing the 35 teeth of the thread picker. When the pressure is released the guard returns to its normal position aiding in cleaning the teeth.

40 Referring to Figure 2. A motor-suction-unit 20 is rigidly joined to a handle 21. Surrounding the handle is a filter sleeve 22 which communicates at its bottom side with a dirt receptacle 23 disposed around the handle and adjacent to the up-draught dirt-laden air duct 24.

45 Figure 3 diagrammatically illustrates the type of floor wheel which is carried by a spindle 30 supported on both ends by a bow or housing 31 held downward by a spring 32.

50 Figure 4 diagrammatically illustrates a yield-

able or retractable wheel mounted on a free-end spindle carried by a shank 35 held downward by a spring 36.

Figure 5 shows the tooth structure of the part 2. 5 Figure 6 shows the blank form of the spring guard 3. It has been found highly practical to make this tooth and spring guard portion of the nozzle a middle section in the forward edge of the nozzle. It may, however, be extended the full 10 width of the nozzle if desired.

Having set forth my invention in clear and simple form, it should be noted that many variations and modifications required by the character of the nozzle and the machine to which it is applied can be provided by those familiar with these arts without departing from the spirit of my invention.

I claim:

1. In a vacuum-cleaner nozzle having an elongated air-inlet slot, forward and rearward carpet-contacting lips defining the long sides of said slot, all the foregoing disposed transversely to the direction of motion of the nozzle when in use, a row of teeth affixed to one of the long sides of said slot but not in normal cleaning engagement with the carpet nap and so positioned that the tips of the teeth are substantially horizontally aligned with, and adjacent to, one of said lips, the said lip affixed to the same said long side and extending between the teeth, normally contacting the carpet undergoing cleaning, and being flexibly yieldable with respect to the nozzle and the teeth when under more than usual upward pressure from the carpet when more than normal downward pressure is exerted by the operator, said yieldability permitting the said teeth to sink into the carpet nap when the said downward pressure is exerted.

2. In a vacuum-cleaner nozzle having an elongated air-inlet slot, forward and rearward carpet-contacting lips defining the long sides of said slot, all the foregoing disposed transversely to the direction of motion of the nozzle when in use, a row of teeth affixed to one of the long sides of said slot but not in normal cleaning engagement with the carpet nap and so positioned that the tips of the teeth are substantially horizontally aligned with, and adjacent to, one of said lips, the said lip normally contacting the carpet undergoing cleaning, being flexibly yieldable with respect to the nozzle and the teeth when under

more than usual upward pressure from the carpet when more than normal downward pressure is exerted by the operator, being joined to the same said long side, and having openings through which the said teeth project when the said pressure is exerted. 5

3. In a vacuum-cleaner nozzle having an elongated air-inlet slot, forward and rearward carpet-contacting lips defining the long sides of said slot, all the foregoing disposed transversely to the direction of motion of the nozzle when in use, a row of teeth affixed to one of the long sides of said slot but not in normal cleaning engagement with the carpet nap and so positioned that the tips of the teeth are substantially horizontally aligned with and adjacent to one of said lips, the said lip being composed of a bent sheet of spring metal affixed to the same said long side, normally contacting the carpet undergoing cleaning, and being flexibly yieldable vertically with respect to 20 the nozzle when under more than usual upward pressure from the carpet when more than usual downward pressure is exerted by the operator, said yieldability permitting the said teeth to sink into the carpet nap when the said downward 25 pressure is exerted.

4. In a vacuum-cleaner nozzle having vertically yielding floor-wheels on its ends and an elongated air-inlet slot, forward and rearward carpet-contacting lips defining the long sides of said slot, said slot and lips disposed transversely to the direction of motion of the nozzle when in use, a row of teeth affixed to one of the long sides of said slot but not in normal cleaning engagement with the carpet nap and so positioned that the 30 tips of the teeth are substantially horizontally aligned with and adjacent to one of the said lips, the said lip being affixed to the same said long side, normally contacting the carpet undergoing cleaning, and being flexibly yieldable vertically with respect to the nozzle when under 35 more than usual upward pressure from the carpet when more than normal downward pressure is exerted by the operator, the yieldability of the said end wheels and the said lip functionally co-operating to permit the said teeth to sink into the carpet nap when the said downward pressure is exerted. 40 45
